UNITED STATES PATENT OFFICE.

FRANK B. HOWELL, OF DETROIT, MICHIGAN, ASSIGNOR TO THE AMERICAN RADIATOR COMPANY, OF NEW JERSEY.

DESIGN FOR A SECTION FOR STEAM-BOILERS.

SPECIFICATION forming part of Design No. 33,786, dated December 25, 1900.

Application filed November 27, 1900. Serial No. 37,935. Term of patent 14 years.

To all whom it may concern:

Be it known that I, FRANK B. HOWELL, a citizen of the United States of America, residing at Detroit, county of Wayne, and State of Michigan, have invented and produced a new and original Design for Sections for Steam-Boilers, of which the following is a specification, reference being had to the accompanying drawings, forming a part thereof, and in

10 which—

Figure 1 is a front elevation of the design, and Fig. 2 is a side or edge elevation thereof.

As shown in the drawings, the leading or material features of the design are as follows:

15 The section is in its general contour oblong rectangular, the shorter sides of the figure being its top and bottom. The upper face of the section is bowed upwardly from end to end, and at its upper corners the section is bowed outwardly or laterally. The sides of

20 the section are inclined inwardly or toward each other at their lower ends, and the lower

face of the section is straight. A plurality of apertures, elongated vertically and arranged across the section and adjacent to its upper 25 end, open transversely through it.

Minor features of the design are the outward inclination of the top and sides of the section from its front and rear faces and a circular aperture transversely through the 30 section midway between its sides and near its top and a similar aperture adjacent to each lower corner.

I claim as my invention—

The design for a section for a steam-boiler, 35 as herein shown and described.

In testimony whereof I have signed my name to this specification in the presence of two subscribing witnesses.

FRANK B. HOWELL.

Witnesses:

CLARENCE CARPENTER,
GEO. G. DIXON.
